US00D864993S

(12) **United States Design Patent** (10) **Patent No.:** **US D864,993 S**
(45) **Date of Patent:** **** Oct. 29, 2019**

(54) **DISPLAY SCREEN OR PORTION THEREOF WITH GRAPHICAL USER INTERFACE**

(71) Applicant: **Samsung Electronics Co., Ltd.**, Suwon-si (KR)

(72) Inventors: **Soomin Kim**, Seoul (KR); **Moonjeong Kim**, Ulsan (KR); **Joonho Ok**, Seoul (KR); **Hyeeun Lee**, Seoul (KR); **Taekyeung Lim**, Seoul (KR)

(73) Assignee: **SAMSUNG ELECTRONICS CO., LTD.**, Suwon-si (KR)

(**) Term: **15 Years**

(21) Appl. No.: **29/628,091**

(22) Filed: **Dec. 1, 2017**

(30) **Foreign Application Priority Data**

Aug. 22, 2017 (KR) 30-2017-0039028

(51) **LOC (12) Cl.** **14-04**

(52) **U.S. Cl.**

USPC **D14/488**; D14/485

(57) **CLAIM**

The ornamental design for a display screen or portion thereof with graphical user interface, as shown and described.

DESCRIPTION

FIG. 1 is a front view of a display screen or portion thereof with graphical user interface showing our new design according to a first embodiment;

FIG. 2 is a front view of a display screen or portion thereof with graphical user interface showing our new design according to a second embodiment;

FIG. 3 is a front view of a display screen or portion thereof with graphical user interface showing our new design according to a third embodiment;

FIG. 4 is a front view of a display screen or portion thereof with graphical user interface showing our new design according to a fourth embodiment; and,

FIG. 5 is a front view of a display screen or portion thereof with graphical user interface showing our new design according to a fifth embodiment.

The outer perimeter shown in broken line in the drawings illustrates a display screen or portion thereof and forms no part of the claimed design. The remaining broken lines in the drawings illustrate portions of the graphical user interface that form no part of the claimed design.

1 Claim, 5 Drawing Sheets
